UNITED STATES PATENT OFFICE.

FRANCIS T. KANE, OF CHICAGO, ILLINOIS, ASSIGNOR TO A. W. ZIMMERMAN, OF CHICAGO, ILLINOIS.

BURNER.

1,119,167.

Specification of Letters Patent.

Patented Dec. 1, 1914.

Application filed July 28, 1913. Serial No. 781,480.

To all whom it may concern:

Be it known that I, FRANCIS T. KANE, a citizen of the United States, and a resident of Chicago, county of Cook, and State of Illinois, have invented certain new and useful Improvements in Burners, of which the following is declared to be a full, clear, and exact description.

This invention relates to burners, and has been designed particularly for use in converting crude oil into a gaseous condition and burning the gas thus generated.

One object is to provide a crude oil burner with means whereby a steam jet may be injected into the body of crude oil to agitate the same, and thereafter to produce pressure in the reservoir containing the crude oil and also in a storage chamber for containing the generated gas, at the same time injecting the gas and purifying it.

Other objects and advantages will appear in the course of this specification and with all of said objects and advantages in view, this invention consists in the several novel features of construction and combination of parts hereinafter fully set forth and claimed.

The invention is clearly illustrated in the drawing furnished herewith, which shows a central vertical section through a burner embodying one form of the present invention.

Referring to said drawing, 10, designates a reservoir for containing a quantity of crude oil, which is to be converted into gas and burned, or otherwise made use of in its gaseous state. The bottom 11, of said reservoir is shown as concavo-convex in form, the concave side being exposed to its exterior. A filler pipe 12, opens to the reservoir and may lead from a suitable tank (not shown) containing a large supply of crude oil, and provided in accordance with the well known practice, with means for continuously supplying the reservoir with oil.

Above the reservoir 10, is a storage tank or chamber 13, connected with the reservoir by a number of tubes 14, through which gas may escape from the reservoir to the storage tank, and extending down from a point near the top of said tank is a gas conducting pipe 15, which leads to a gas burner 16, located below the concave bottom 11 of the

reservoir. In the form illustrated in the drawing, the gas conducting pipe 15, leads down through the bottom of the tank 13, and through the top and bottom of the reservoir and is provided with a flange 16, bolted to the bottom of the reservoir. The open top of the pipe 15, is arranged to be closed by a valve 17, upon the end of a screw threaded valve stem 18, threaded in the top of the tank 13, and having a hand wheel 19, upon its outer end by which the valve may be raised or lowered to control the passage of gas to the pipe 15, and to entirely close said passage.

The burner 16, is shown in the form of a flat, hollow, circular body, having an air inlet 20, in its bottom wall 21, and apertures 22, in its top wall 23, for the escape of the gas. The lower end of the gas pipe 15, flares outward, as at 24, and merges into the top wall 23, of the burner 16; a circular diaphragm 25, is located in the hollow of the burner 16, approximately midway between its top and bottom dividing the chamber thereof into two passage ways, the lower passage way conducting air from the air inlet 20, to the gas passage above the diaphragm, when it mixes with the gas. The diaphragm is supported from the bottom wall 21, and at its center is of cone like formation, substantially paralleling the curve between the pipe 15, and wall 23, and its peripheral edge is curled upward to deflect the gas toward the apertures 22.

Surrounding the reservoir 10, is a water jacket, which may comprise a water chamber 26, and located above said reservoir is a drum 27, connected to said water jacket by one or more pipes 28. The drum is preferably formed with a steam dome 29, in its top, and leading down from said steam dome is a steam pipe 30, which opens into the reservoir 10, preferably below the level of the oil therein.

The burner may be employed for many purposes and it is here shown as used for heating water contained in the jacket 26, which may be connected to any container by a feed pipe 31, and return pipe 32.

In operation, the reservoir is partly filled with crude oil, (and thereafter constantly supplied with oil as the supply in the reservoir decreases) and preferably the storage tank 13, and reservoir 10, are charged with

a gas under pressure through the pipe 12, and the valve 17, closed.

To use the burner, the valve 17, is opened and the gas issuing from the apertures 22, 5 is ignited. The heat of the gas flame heats the crude oil in the reservoir and heats the water in the jacket. Volatilization of the crude oil is caused by the heat, radiated thereto, and steam is generated in the water 10 jacket, which steam rises to the top of the dome 29, and passes through the pipe 30, from which it is discharged into the reservoir agitating the crude oil; as the pressure in the device lowers, (from the escape of 15 the gas through the perforations 22) the pressure from the steam increases and forces the volatilized crude oil up through the tubes 14, into the tank 13, and out through the gas pipe 15, and perforations 20 of the burner, 16, where it is consumed. The intermingling of the steam with the gas appears to have a purifying action on the gas and produces a blue, clear, hot flame.

25 I realize that various alterations and modifications of this burner are possible without departing from the spirit of my invention, and I do not, therefore, desire to limit myself to the exact details of construction shown and described.

30 I claim as new and desire to secure by Letters Patent:

35 1. A crude oil burner, comprising an oil reservoir, a gas burner therebelow, a gas storage tank thereabove communicating with the reservoir, and a valve controlled gas pipe leading from the top of said storage tank through said reservoir and to said gas burner.

40 2. A crude oil burner, comprising an oil reservoir, a gas burner therebelow, a gas storage tank communicating with said reservoir, a valve controlled pipe leading from said tank to said burner, a water jacket

surrounding said reservoir, a drum and 45 tubes connecting said drum with said jacket, and a steam jetting pipe leading from the top of said drum and opening to said reservoir.

3. A crude oil burner, comprising an oil 50 reservoir, a gas burner therebelow, a gas storage tank communicating with said reservoir, a valve controlled pipe leading from said tank to said burner, a water container surrounding said reservoir and having a 55 steam dome thereabove, and a steam jetting pipe leading from said steam dome and opening to said reservoir.

4. A crude oil burner, comprising an oil reservoir, having a concave bottom, a gas 60 storage tank above said reservoir and connected thereto by a plurality of tubes, a valve controlled gas pipe leading from the top of the interior of said storage tank to a point directly below the bottom of said 65 reservoir, and a gas burner at the bottom of said pipe opening thereto and having gas apertures in its upper wall and an air inlet in its lower wall, said upper and lower walls being separated by a diaphragm the 70 edge of which is spaced away from the sides of the burner wall.

5. In a crude oil burner, the combination of an oil reservoir, a steam jetting pipe opening thereinto, means for supplying 75 steam to said pipe, a gas storage tank above said reservoir, communicating therewith through a plurality of tubes, a valve controlled gas pipe leading from said reservoir to a point below said reservoir and a gas 80 burner on the end of said pipe arranged to direct the flames toward the bottom of said reservoir.

Chicago, July 25, 1913.

FRANCIS T. KANE.
